DESIGN FOR A PITCHER OR SIMILAR ARTICLE

Paul Huntington Genter, Denver, Colo., assignor to The Red Wing Potteries, Inc., a corporation of Minnesota

Application June 19, 1939, Serial No. 85,552

Term of patent 3½ years

To all whom it may concern:

Be it known that I, Paul Huntington Genter, a citizen of the United States, residing at Denver, in the county of Denver and State of Colorado, have invented a new, original, and ornamental Design for a Pitcher or Similar Article, of which the following is a specification, reference being had to the accompanying drawing, forming part thereof, and in which

I claim:

The ornamental design for a pitcher or similar article, substantially as shown.

P. H. GENTER.
